UNITED STATES PATENT OFFICE.

JACK WILLIAMS, OF CHESTER, ENGLAND, ASSIGNOR TO WILLIAMS & WILLIAMS LIMITED, OF CHESTER, ENGLAND, A COMPANY OF GREAT BRITAIN.

WINDOW.

Application filed December 4, 1926, Serial No. 152,651, and in Great Britain March 8, 1926.

This invention relates to windows of the kind comprising a lower sash mounted to hinge or pivot about the bottom member of the window frame or sill and an upper sash 5 mounted in a frame and so connected to the lower sash by links pivoted between their ends to the side members of the frame that when one sash moves the other moves to a corresponding extent.

10. A window according to this invention comprises a lower sash hinged at its lower end to the window frame or sill, an upper sash mounted in the frame upon sliding pivots and one or more links pivoted at a point 15 between their ends to the side members of the frame and connected at their ends to the sashes. The connecting links are attached to the lower sash by means of sliding pivots and to the upper sash by means of simple 20 stationary pivots.

Preferably the sliding pivots comprise blocks adapted to slide in grooves or channels formed in the sash frames and in the case of metal windows these grooves are conveniently provided by employing frame 25 members of a suitable channel section.

The invention may be carried out in various ways but one construction according thereto is illustrated diagrammatically by 30 way of example in the accompanying drawing, in which the window is shown in side elevation.

In the construction illustrated in the drawing, the window comprises two metal sashes 35 A and B and a metal frame C all formed of suitable channel section. The lower sash A is hinged to the frame at its lower end and the upper corners of the upper sash are pivoted to blocks C¹ mounted to slide in the 40 channels in the side members of the metal frame C. Links D centrally pivoted to the frame connect the two sashes A and B at each side. The upper ends of the links D are pivoted to the upper sash B at D¹ and 45 their lower ends are pivoted at D² to sliding blocks A¹ mounted to slide in grooves conveniently provided by the channel section side members of the lower sash A. When the window is shut both sashes lie in the

same plane, the blocks C¹ being at the top 50 of the channels in the frame and the blocks A¹ at the bottom of the channels in the sash. To open the window the lower sash A is swung inwards on its hinges. This causes 55 the links D to turn about their central pivots so as to swing the upper sash B outwards on its pivot, the blocks A¹ and C¹ sliding in their respective channels to permit of this movement. Thus any movement of the lower sash A causes a simultaneous corresponding movement of the upper sash B. 60

It will be understood that instead of being actually hinged or pivoted to the window frame, the lowermost sash may rest on the bottom rail of the frame so as to turn 65 or rock thereon when the window is opened without forming a gap in so doing.

With a window in accordance with this invention, as there is no gap or opening between the sill and the bottom rail of the sash 70 when the window is open, draught excluding wings of the known type can be used for the bottom sash if desired.

What I claim as my invention and desire to secure by Letters Patent is:— 75

1. In a sash window the combination of a frame, a lower sash hinged at its lower end to the said frame, an upper sash, pivots on which the upper sash is mounted to slide in the frame, and links pivoted at a point 80 between their ends to the side members of the frame and connected at their ends to the sashes.

2. In a sash window the combination of a frame, a lower sash hinged at its lower end to the said frame, an upper sash, blocks to which the upper sash is pivoted, the said blocks being mounted to slide in channels formed in the side members of the window frame, links pivoted at a point between their 85 ends to the side members of the frame and at their upper ends to the upper sash, and blocks mounted to slide in channels formed in the side members of the lower sash frame, the lower ends of the links being pivoted to 90 the said blocks.

3. In a sash window the combination of a frame, a lower sash hinged at its lower

end to the said frame, an upper sash, blocks to which the upper sash is pivoted at its upper end, the said blocks being mounted to slide in channels formed in the side members of the window frame, links pivoted at a point between their ends to the side members of the window frame and at their upper ends

to the upper sash, and blocks mounted to slide in channels formed in the side members of the lower sash frame, the lower ends of the links being pivoted to the said blocks.

In testimony whereof I have signed my name to this specification.

JACK WILLIAMS.
